UNITED STATES PATENT OFFICE

111,076

DESIGN FOR A PORTABLE REFRIGERATOR INDIVIDUAL ICE CREAM SHELF UNIT

George B. Hume, Kansas City, Mo.

Application June 13, 1938, Serial No. 77,804

Term of patent 14 years

To all whom it may concern:

Be it known that I, George B. Hume, a citizen of the United States, residing at Kansas City, Jackson County, Missouri, have invented a new, original, and ornamental Design for a Portable Refrigerator Individual Ice Cream Shelf Unit, of which the following is a specification, reference being had to the accompanying drawing, forming a part thereof.

The figure is a perspective view of a portable refrigerator individual ice cream shelf unit, showing my new design.

I claim:

The ornamental design for a portable refrigerator individual ice cream shelf unit, as shown.

GEORGE B. HUME.
